UNITED STATES PATENT OFFICE

NATHAN G. BURGSTER, OF CHICAGO, ILLINOIS

METHOD OF ELIMINATING STATIC ELECTRICITY FROM COMBUSTIBLE ROOFS

Application filed April 4, 1928. Serial No. 267,359.

This invention relates to a method of eliminating static electricity from the non-metallic roofs or other surfaces of oil storage tanks and other structures.

5 An object of the invention is to provide a method of applying a continuous unbroken surface of metal over a non-metallic surface for eliminating the hazardous effect of static electricity.

10 Another object of the invention is to provide a method of eliminating fire hazards resulting from static electricity.

15 A further object of the invention is to provide a method of protecting oil storage tanks and other structures against static electricity.

The invention consists in covering a non-metallic tank roof or a similar surface with a coating or film of metal, which is continuous and unbroken over the entire roof or top of the tank, for establishing an electrical conductor whereby static electricity will be conducted to the eaves of the roof whence it is led to the ground through either the 25 metallic walls of the structure or other conductors.

I do not limit my invention to oil storage tanks, as it is applicable to any kind of building structure having a non-metal roof 30 and where it is desirable or necessary to eliminate static electricity as a fire hazard. The metal may be applied in various ways.

The metal may be melted and applied in such state by spraying it over the surface 35 face to be protected, or the melted metal may be applied in other suitable manners. Metal foil may be used, in which event it is secured in place by its own adhesiveness or by suitable adhesive material. The metal 40 may be zinc, aluminum, copper and the like.

Some roofs are made of sheets of non-metallic material or of metallic material or of metallic coated material laid with overlapping joints. Roofs so constructed may 45 be protected by my method, in which event the metal is sprayed or otherwise secured over the edges of such sheets, with all the metal so used to make a continuous unbroken grill-work over the surface.

50 The metallic film or coating applied by

my process is secured in position by adhesion without the use of nails, clamps or the like, such security resulting from the method of application.

The metal may be reduced to fine particles 55 and mixed with a suitable carrier whereby the same may be applied to the desired surface. Metal dust may be used if desired, and is applied by any suitable apparatus such as a spray. The drawings show generally two forms of application of the method of my invention.

On the drawings:

Figure 1 is a side elevation of a well-known type of oil storage tank.

Figure 2 is an enlarged fragmental vertical section through an upper corner of a tank, showing the metal covering of my invention in place.

Figure 3 is a top plan view of a tank, 70 the roof of which is constructed of sheets of material laid with overlapping joints, over which joints the metal conducting grill-work of my invention is applied.

Figure 4 is an enlarged vertical section 75 through one of the joints of Figure 3, showing the manner of applying the metal conductor of my invention.

As shown on the drawings:

The tank of Figure 1 comprises side 1 and 80 top 2, constructed in the usual manner.

Figure 2 shows wooden uprights 3 carrying roof beams 4, on which roof beams is laid the wooden roof 5.

The outer shell of the tank is made up of 85 steel plates for the sides 6 connected in the usual manner.

Composition material 7 is laid on top of the wooden roof 5 and over this composition is applied the metallic coating or layer 90 8 of my invention.

The construction shown in Figure 2 includes angle bars 9 suitably secured to the side walls 6 of the tank, with bolts 10 passing through the bars 9 and fastening thereto to the composition roof 7. A strip 11 of metal is laid over the margins of the composition roof, so that the bolts 10 will not tear the composition.

95 The metallic layer is applied over the en- 100

tire top 2 of the tank and at its margins over the bars 11 and bolts 10, and extends downwardly a sufficient distance to make electrical connection with the side wall 6 of the tank.

5 Any static electricity will flow to the margins of the layer 8 on the roof and be conducted therefrom to the ground through the wall 6 of the tank.

10 Should the structure have side walls of non-metallic material, then suitable conductors such as cables may be connected to the coating 8 and carried to the ground, where suitable connection is made.

15 The roof shown in Figure 3 comprises a plurality of sheets 12 laid up with overlapping joints as shown best in Figure 4. Where these sheets are of metal, the metal coating of my invention is applied over the overlapping edges or joints of these sheets, forming a grill-work or skeletonized covering, comprising the long members 13 and the shorter transverse connecting members 14. The metal coating is applied as shown in Figure 4 to cover the overlapping ends of the sheets 12, and at the same time to be securely fixed by adhesion to the roof.

20 The members 13 and 14 of this form of roof coating are secured at the ends thereof to the metallic side wall 6 of the tank, as described with reference to Figure 2, or may be connected by suitable cables not shown with the ground.

25 The metal coating is secured in position on the roof by adhesion, and being continuous and unbroken serves to conduct any static electricity to the ground, thus eliminating fire hazards.

30 Most fires of wood top oil tanks are caused by lightning, not so much from being directly hit thereby, but because the static electricity ignites the gases issuing from the tanks.

35 Any metallic fitting on the roof must be electrically connected to the metal coating of my invention. This connection may be readily made when the metal is sprayed.

40 The term oil storage tank used herein and in the appended claims includes any tank or reservoir for storing inflammable liquids.

45 The term "composition material" is used herein generally, and includes any material used for covering the wooden roof of the storage tank.

50 While I have described more or less precisely the details of construction of my invention yet I do not wish to be understood as limiting myself thereto, as I am aware that changes may be made in the proportion of parts and that materials may be substituted without departing from the spirit and scope of my invention.

55 I claim as my invention:

60 The method of protecting roofs of oil tanks and the like against damage by light-

ning and static electricity which tanks have roofs of non-metallic material, which consists in spraying a continuous unbroken thin electrical conductor over all of said roof, and joining the conductor to a ground.

65 In testimony whereof I have hereunto subscribed my name at Chicago, Cook County, Illinois.

70 NATHAN G. BURGSTER.
